UNITED STATES PATENT OFFICE

LEONARD B. HARRIS, OF NEW YORK, N. Y., ASSIGNOR TO H. O. G. HOLDING CORP., OF NEW YORK, N. Y., A CORPORATION OF NEW YORK

OIL GAS GENERATOR

Application filed February 2, 1931. Serial No. 512,897.

This invention relates to an oil gas generator for generating oil gas from hydrocarbon oils by causing same to react with steam, under heat influence.

5 The mixture of the oil and steam is heated to a high temperature by means of moving heating elements with which the oil and steam are brought into actual contact in the form of a mixed spray or atomized vapor, said 10 heating elements being in motion in a heated gas-making generator.

The heat in the generator is used to flash water into steam in its passage through a heating grid placed inside the generator.

15 The oil and steam are projected into direct contact with the moving heating elements, as a mixed spray of oil and steam preferably by means of a cam-operated, intermittently-timed, single-acting differential plunger

20 pump. This pump is timed to project the oil and steam onto the moving heating elements at a predetermined point in the movement of the heating elements thus synchronizing the joint contact of the mixed spray of oil and steam, and the heating elements. The smaller diameter plunger of this differential pump forcing the hydrocarbon intermittently in a regulated quantity through an adjustable orifice nozzle, so constructed

25 that the spray or jet from this nozzle will be spread over the entire coincidently-presented surface of the heating element, when said heating or resistance element is in an incandescent state.

30 While electric heating elements are shown in this application the applicant does not wish to confine himself to electric heating only as other means can be used for providing the heat.

35 The larger diameter plunger of the differential pump will deliver water intermittently in a regulated quantity to the heating grid, inside the generator, from which grid it issues in the form of steam in multiple jets into the path of the oil spray to be combined with same and projected on to the heating element, as a mixture of oil and steam.

An object of this invention is to intermittently deliver a regulated quantity of water 50 into an elongated heating grid in a heated

gas-making generator, the water being flashed into steam during its passage through the grid, each intermittent delivery of water into one end of the heating grid causing a corresponding puff of steam to be discharged 55 in jets from the other end of the grid.

Another object of this invention is to intermittently deliver a regulated quantity of hydrocarbon oil into the gas-making generator and to cause the oil to pass through an 60 atomizer nozzle and to project into the generator in the form of a mistlike spray.

Another object of this invention is to provide means for synchronizing the delivery of the relatively proportioned quantities of hydrocarbon spray and the jets of steam, and to cause the projected oil spray and the jets 65 of steam to meet and commingle and form a mixed spray of oil and steam.

Another object of this invention is to 70 cause the mixed spray to come into direct contact with a portion of the external surface of an incandescent heating element and causing the steam to dissociate into hydrogen and oxygen and reaction between hydrogen and 75 carbon.

Another object of this invention is to mount a plurality of said heating elements in the gas-making generator and to cause said heating elements to be successively moved 80 into and out of the path of the mixed spray.

With the above and other objects in view the invention will be hereinafter more particularly described, and the combination and arrangement of parts will be shown in the 85 accompanying drawings and pointed out in the claims which form part of this specification.

Reference will now be had to the drawings, wherein like numerals of reference designate 90 corresponding parts throughout the several views in which:

Figure 1 is a side view in elevation of my oil gas making unit, showing the oil gas generator, first and second stage oil and water 95 pumps, water seal, scrubber, and gas bag or bellows; the oil gas generator, water seal and scrubber being in section, the section being taken as on line 2-2 in Figure 3, and the gas bag being shown as partly broken away. 100

Figure 2 is a side elevation of the gas bag, partly broken away.

Figure 3 is a plan view showing the general arrangement of my oil gas making unit 5 with the oil gas generator partly broken away to show the mixed spray.

Figure 4 is an enlarged section of the second stage oil and water pumps and shows an oil spraying diagram, the section being taken 10 as on line 2-2 in Figure 3.

Figure 5 is an enlarged sectional view of a diaphragm pump, one of which is used as a first stage oil supply pump, and another of which is used as a first stage water supply 15 pump.

Figure 6 is a side view in elevation of the oil gas generator, partly in longitudinal section along the shaft and shows a movably mounted heating element and the planetary 20 mechanism for moving said element. The upper portion of the oil gas generator being partly broken away to show a portion of the heating grid.

In the drawings, reference character 10 indicates an oil gas generator comprising a gas-tight metal container 11, preferably of cylindrical shape and having covers or end plates 12, 12, through the center of which passes a hollow shaft 13. Gas-tight packings 14, 14, 25 at both ends of the shaft 13, prevent leakage of the gas around the shaft. On one end of shaft 13, there has been mounted a sprocket gear 15 driven by chain 16 from a sprocket pinion 17 on the pump shaft 18, and causing shaft 13 to revolve, as best shown in Figure 3. The number of revolutions per minute of the shaft 13 is equal to the number of 30 strokes per minute of the differential second stage oil and water pump 19, divided by the number of heating elements used in the oil 35 gas generator 10. In the embodiment shown, two elements 20, 20, are used and thus making the number of revolutions per minute of the shaft 13 one-half the number of strokes 40 of the oil and water pump 19.

The oil gas generator 10 has on its upper top side 21 an extension trunk 22 forming a receptacle on its inside for the water-heating 45 grid 23. The upper side 21 is provided with a flange 24 adapted to receive a water seal or trap member 25 to which is fastened a scrubber or washer 26.

As best shown in Figure 1, a gas conduit 27 leads from the scrubber 26 to a flexible gas bag or bellows 28; the functioning of this flexible gas container being to store a small quantity of gas and being flexible will by its expansion and contraction operate the various 50 time-o-stats or instruments controlling the operation of my self-contained oil gas generator as a whole, as described under operation.

A motor 29 is used for driving the mechanism of the oil gas generator 10, said motor 55 operating through a reducing gear 30, which

in turn operates the differential second stage oil and water pump 19, and also the first stage oil supply pump 32, and the first stage water supply pump 33. The whole apparatus being mounted on a suitable foundation 70 plate 34. Fixedly mounted on the shaft 13 in the oil gas generator 10 are disc-shaped members 35, 35, made of insulation material. These disc-shaped members revolve with the shaft 13 in the manner of the arm of a 75 planetary gear assembly.

On diametrically opposite points of the discs 35, 35, are pivot pins 36, 36', of a heat-resisting metal, each pin being rotatably housed in a bushing 37 fixed in the discs 35, 35. Planet pinion gears 38, 38, made of insulating and heat resisting material are fastened to the pins 36, 36', by means of nuts 39, 39.

The planet pinions 38, 38, engage centrally located stationary sun gears 40, 40, made of insulation material, one sun gear being mounted at each end of the oil gas generator 10, and secured by means of screws 41, 41, to the bearing arms 42, 42, fastened to the internal flanges 43, 43, of the container 11, by means of screws 44, 44.

The bearing arms 42, 42, extend diametrically and act as secondary bearings, allowing all the mechanism to be mounted and mechanically operated and inspected while the cover plates 12, 12, are removed.

While the pivot pin 36 is shown as having no end play, pivot pin 36' can be moved endwise through its bushing 37 so as to allow the heating elements 20, 20, to be inserted between the pivot pins 36 and 36', and in this way the heating elements 20, 20, will revolve with the pins 36, 36', being driven by the pinion gears 38, 38, which in turn are caused to revolve by engaging with the stationary sun gears 40, 40, and being driven around said sun gears by the disc members 35, 35, fastened to the shaft 13.

Electric leads 45, 45' are brought into the oil gas generator 10 through the hollow shaft 13, from a contact plug 46, mounted at the sprocket end of shaft 13. The plug 46 revolves with the shaft 13. The electric leads 45, 45', pass through holes 46, 46, in the shaft 13, and are contacted to contact plates 47 and 47' secured to discs 35, 35, under bearing shoulders 31, 31', of the pins 36 and 36'. Contact plate 47' is formed to act as a spring to provide a pressure against the end of the heating element 20, as best shown in Figure 6.

Electric current from the leads 45, 45' flows through the contact plates 47 and 47' through screws 48, 48, through ring plates 49, 49, secured to the disk members 35, 35, and furnishes a continuous supply of electric current to any plurality of electrodes or heating elements 20, 20, which may be mounted between the discs 35, 35.

It will be seen that owing to the planet pinion 38, being of a smaller diameter than the fixed sun gear 40, the electrodes 20, in revolving will present a different surface to the hydrocarbon oil spray and to the steam at each revolution, as will be explained later under operation.

10 Each end of shaft 13 is plugged to make it gas-tight after the electric wires 45 and 45' have been inserted.

In the upper part of the container 11, is the coil or water heating grid 23 made of piping 50 which is supplied with water from the water pump 51, best shown in Figure 4, the object being that the hot gas from the oil gas generator 10, in passing on its way to the scrubber 26 will convert the water in the grid 23 into steam, and at the same time assist in cooling the gas.

20 The steam will pass through the hot grid piping 50, in a measured or regulated quantity and pressure to a row of orifices 52 in the lowest pipe 53 of the grid 23, as shown in Figures 3 and 4. The pipe 53, having the orifices 52 is positioned inside the oil gas generator 10 longitudinally across and adjacent to the oil spray 54 issuing from a nozzle 55 so that the oil spray will pick up the steam jets 56, and commingle with each other, and form a mixed spray 57 of oil and steam before striking the heating elements 20.

As best shown in Figure 3, the oil gas generator shaft 13 has a chain drive sprocket 15 and chain 16 driven by sprocket 17 on the drive shaft 18 of the differential second stage pump 19. As only two heating elements are shown in the oil gas generator 10, this chain drive is therefore a two to one ratio. Shaft 40 18 of the differential pump 19 is mounted in side plates 59, 59, comprising brackets 66, 66, for securing to the foundation plate 34. The side plates 59, 59, are bolted to the pump body 60, which has a chamber 61 therein in which a cam 62 on shaft 18 is adapted to rotate, as best shown in Figure 4.

Cam 62, contacts with a roller 63, mounted on a pin 64; the roller 63 and pin 64 being mounted in the enlarged portion 65' of the differential plunger 65, 65'.

The differential plunger 65, 65' is constructed with a small diameter front end 65, reciprocating in a nose piece member 70, to act as second stage oil pump 67, and with plunger 65' of larger diameter, reciprocating in pump body 60, to act as second stage water pump 51, both pumps being operated together on their delivery stroke by the cam 62 and returned on intake stroke by a spring 68.

The small diameter front end 65 of the differential plunger 65, 65' operates through packings 69 in a chamber 91, of the pump body 60. Pump body 60 has a flange 71 for 65 securing the differential pump 19 to a flange

72 of the extension 73 of the oil gas generator 10.

The nose piece member 70 has a flange 74 secured between the flanges 71 and 72. At the front end of the nose piece member 70, inside the generator extension 73 of the oil gas generator 10, is a thread 75, in which is screwed a retaining nut 76 of suitable form to retain in position in the nose piece 70, a split atomizer nozzle shown in entirety as 55, and consisting of two parts 77, 77'. The nut 76 and split nozzle 55 are brought up against soft metal washers 78, and 79, so that by exerting pressure with the nut 76, against a conical surface on the outside of the split atomizer nozzle 55, the thickness of the fan-shape oil spray can be changed. Tightening the nut 76 brings the parts 77, 77' of the split nozzle 55 in closer relation with each other, and causes a finer oil spray. Within the split nozzle 55, the front end 65 of the differential plunger 65, 65', reciprocates, thereby causing a pressure and discharging the oil in the form of an atomized mistlike spray of fan-shape form, as shown in Figure 3.

Oil is fed to the atomizer nozzle 55 through apertures 80, 81 and 82, from an inlet check valve 83, and a regulating needle valve 84, attached to the pump body 60. The needle valve 84 is supplied with oil from the first stage oil supply diaphragm pump 32, through pipe 85, and through a delivery check valve 86, best shown in Figure 3.

In the differential second stage pump 19, shown in Figure 3, the shaft 18 ends in a coupling 87 connecting it with the shaft 88 of the reducing gear 30. The reducing gear is driven by shaft 89 through coupling 90 and motor 29. Shaft 88 of the reducing gear 30 is extended into a casing 92 adapted to house a cam 93. 100 105

As shown in Figure 5, the cam 93 actuates two bell cranks 94, 94'. Bell crank 94 operates the first stage oil supply pump 32, through links 95. The oil pump 32 gets its supply of oil through inlet check valve 96, and through regulating valve 97. Bell crank 94' operates the first stage water supply pump 33, in the same manner, getting its supply of water through inlet check valve 96' and regulating valve 98, and delivering through check valve 86' to water line 99, shown in Figure 3. 110 115

The construction of the first stage oil and water diaphragm pumps 32 and 33, is best shown on Figure 5, which shows a diaphragm 120 100, a glass vacuum reservoir 101, a strainer 102, inlet 103, and delivery 104.

The first stage oil and water pumps 32, and 33, used in combination with the other apparatus, are duplicates of a preferred type 125 of pump. It will be understood, however, that other types of pumps could be used for the first stage delivery of oil and water.

As best shown in Figure 1, the water seal member 25, is bolted to the top flange 24, of 130

the oil gas generator and has a passage 105, through which the gas passes into a water seal bend 106, contained therein. An overflow connection 107, has been provided 5 on one side of the water seal member 25, to allow overflowing into a U-shaped pipe 108. An internal flange 134, has been provided to carry a perforated plate 109, acting as a support for the scrubber medium 110. The 10 scrubber 26, has its flange 111, bolted to the flange 112, of the water seal member 25. The scrubber 26, is provided at its upper end with a cover plate 113, to which is secured an outlet pipe 114, connected to the gas conduit 27, and 15 an inlet pipe 115, to admit water to a spray ring 116, which sprays on a perforated plate 117, so that water is distributed over the entire cross-section of the scrubber. Water is supplied to the scrubber 26, from the dia- 20 phragm pump 33, through a pipe 99, and regulating valve 118.

In the pipe 99, best shown in Figure 3, is a T-fitting 119, distributing some of the water from the diaphragm pump 33, through a pipe 25 120, through inlet check valve 121, and regulating valve 122, to the second stage water pump 51. The water from the pump 51, being delivered through a check valve 123, through a pipe 124, and a regulating valve 30 125, to the water heating grid 23, in the upper part of the oil gas generator 10.

The gas bag or bellows 28, comprises outer retaining casings 126, and 126', a flexible bag 127, of suitable gas-tight material and having 35 an inlet 128, and outlet 129. At the center of the bag where the expansion and contraction is most effective, there has been provided a rod 130, having a spring 131, fastened thereto and being connected at its free end to a 40 suitable pressure switch 132, which controls the supply of electric current for starting and stopping the gas-making unit as a whole. A threaded handwheel 133, against which the spring 131, reacts, serves for setting the pressure at which the gas bag or bellows 28, will 45 operate the pressure switch 132.

It is to be noted that the nozzle 55, is split in an axial direction so as to form a ribbon-like slot or orifice 136, between the two nozzle 50 parts 77, and 77', and that the nozzle is of the constantly-open type. The nozzle 55 is positioned at the discharge end of the pump 67, so that the front end of the differential plunger 65, 65', is central with and reciprocates in the nozzle. The axis of the nozzle is tangent to the periphery of rotation of the heating elements.

The operation of the oil gas making unit as a whole is as follows: The gas bag 28, 60 when empty, will be collapsed, thereby operating the pressure switch 132, so as to cause a continuous supply of electric current to flow through the lead 45, through the heating elements 20, 20, bringing them to a pre-deter- 65 mined temperature, also heating the gas-tight

and air-tight oil gas generating chamber 11.

When the desired temperature has been reached in the chamber 11, the thermo-switch 135 will contact and cause an electric current to flow through the motor 29, and start it up. 70 The motor 29 will drive through the reduction gear 30, the oil pump 32, and water pump 33, delivering the oil and water to the differential second stage or measuring pump 19.

The pumps 51 and 67, as well as the heating elements 20, 20, in the oil gas generator 10, are driven by the same mechanism from the motor 29, and will function as follows: Pump 51 will deliver a measured quantity of 75 water intermittently to the heating grid 23, where it will be flashed into steam and forced out of the orifices 52 in the lowest pipe 53, at each stroke of said pump, as best shown in Figure 4.

Pump 67, will simultaneously deliver a 80 measured quantity of oil intermittently through the axially split nozzle 55 through a ribbon-like slot or orifice 136, between the two parts 77, 77' of the nozzle, and forming an atomized fan-shaped oil spray 54. The 85 quantity of oil delivered into the oil gas generator 10 by the pump 67 is regulated by the valve 84. The quantity of water delivered to the oil gas generator 10 by the pump 51 is regulated by the valve 122. The 90 first stage pumps 32 and 33 both automatically cut out if overloaded either by excess pressure or excess quantity of liquid taken in, under which conditions the toggle links 95 100 collapse and cause the diaphragm 100 to stop pulsing, as best shown in Fig. 5.

The oil spray 54 will commingle with the 105 steam jets 56 from the orifices 52, and together as mixed spray 57, come in contact with the heating elements 20 and cause the steam to dissociate. It being understood that the heating elements 20 are geared to revolve around the axis of the generator and so timed as to synchronize with the intermittent strokes of the differential pump 19, and to 110 cause one of said elements to pass through the line of mixed spray 57 during the delivery stroke of said differential pump.

Furthermore, each heating element 20 is 115 being rotated on its own axis so as to present a different portion of its heated surface to the line of mixed spray 57 during each revolution. As the spray 57 comes in contact with a heating element 20, when it is in an incandescent state, the steam will be dissociated and gas will commence to form immediately and continue to be given off while the elements continue in their circular path.

The gas after being given off from the heating elements will pass out of the generator by 125 volume, and may be impelled on its way by revolving vanes 137, shown in Figure 1.

Hot gas passing over the external surfaces of the grid 23 will cause the water in the grid to be heated. The gas will pass 130

through the gas passage 105 of the trap or seal member 25 and thence through the seal pipe 106, one end of which is secured by flange 138 to the seal member 25, and the 5 other end remaining open, but extending below the water level indicated by W. L. The oil gas will then rise through the scrubber 26 meeting the wash water spray descending through scrubber medium 110 from spray ring 116, then will pass out through outlet pipe 114 and conduit 27 to the gas bag or bellows 28. This bag 28 will become expanded as it fills with gas and will operate the switches and cut off the entire supply 10 of electric current, both to the heating elements 20 and to the motor 29, thereby stopping the gas making, but leaving the switches in such a condition that when the gas bag 28 collapses the current will again be caused to 15 flow and the gas making automatically started again. The gas bag 28 from its outlet 129 can be connected to any size gas container, which on being filled or emptied will act on the gas bag 28, in combination, to start and 20 stop the gas plant. It will be understood, however, that when the bag 28 collapses and throws in the pressure switch 132, sending current into the heating or resistance elements 20, 20, that the motor 29, pump 19, and 25 the driving mechanism for the said elements will not commence to operate until the heat in the generator has reached the predetermined temperature at which the thermo-switch 135 is set. On reaching this temperature, the thermo-switch 135 will start the motor and the driving mechanism. In other words, the pressure switch 132 can cut off the 30 entire electric current supply, but cannot start the motor 29 without the cooperation of 35 the thermo-switch 135.

It is to be noted that during the movement of a heating element 20, in the circular path 139, that, when the element commences to pass through the line of mixed spray 57, gas commences to form and continues to be given off for a distance after leaving the line of mixed spray, or through a zone 140, as best shown on diagram, in Figure 4. During the remainder of the travel in the circular path 139, the heating element passes near the pipes 50 in the heating grid 23, and turns the water in said grid into steam.

I claim:

1. In apparatus for generating oil gas, an oil gas generating chamber, a plurality of continuously heated heating elements rotatably mounted in said chamber, each heating element being alternately brought into an oil spraying zone in said chamber and out of said zone into a non-spraying zone.

2. In apparatus for generating oil gas, an oil gas generating chamber, a plurality of electrically heated heating elements provided with a continuous supply of electric current and rotatably mounted in said chamber

65 70 75 80 85 90 95 100 105 110 115 120 125 130

ber, each heating element being alternately brought into an oil spraying zone in said chamber and out of said zone into a non-spraying zone.

3. In apparatus for generating oil gas, an oil gas generating chamber, a plurality of electrically heated heating elements provided with a continuous supply of electric current and being rotatably mounted in said chamber, means for causing an oil spray to be intermittently projected into said chamber against one of said heating elements, and means for synchronizing the joint contact of said heating element and said oil spray.

4. In apparatus for generating oil gas, an oil gas generating chamber, a plurality of electrically heated heating elements provided with a continuous supply of electric current and being rotatably mounted on an axis in said chamber, each heating element being alternately brought into an oil spraying zone in said chamber and out of said zone into a non-spraying zone, each of said heating elements being caused to revolve while in motion around its axis in the oil gas generating chamber.

5. In apparatus for generating oil gas, an oil gas generating chamber, a plurality of electrically heated heating elements provided with a continuous supply of electric current and being rotatably mounted in said chamber, means for causing an atomized oil spray to be intermittently projected into said chamber against one of said heating elements, means for causing said elements to revolve and means for synchronizing the joint contact of said moving heating elements and said intermittent oil spray.

6. In apparatus for generating oil gas, an oil gas generating chamber, a plurality of elongated electrically heated heating elements provided with a continuous supply of electric current and being rotatably mounted in said chamber, means for causing an atomized, thin, fan-shape, oil spray to be intermittently projected into said chamber against one of said elongated heating elements, means for causing said elements to revolve and means for synchronizing the joint contact of said moving heating elements and said intermittent oil spray.

7. In apparatus for generating oil gas, an oil gas generating chamber, a plurality of elongated electrically heated heating elements provided with a continuous supply of electric current and being rotatably mounted in said chamber, means for causing an atomized, thin, fan-shape, oil spray to be intermittently projected into said chamber against one of said elongated heating elements, means for causing said elements to revolve and means for synchronizing the joint contact of said moving heating elements and said intermittent oil spray, said atomizing means comprising an axially-split nozzle

forming a ribbon-like slot and the axis of said nozzle being tangent to the periphery of rotation of said heating elements.

8. In apparatus for generating oil gas, an oil gas generating chamber, a plurality of elongated electrically heated heating elements provided with a continuous supply of electric current and being rotatably mounted in said chamber, means for causing an atomized, thin, fan-shape, oil spray to be intermittently projected into said chamber against one of said heating elements, means for causing said elements to revolve and means for synchronizing the joint contact of said moving heating elements and said intermittent oil spray, said atomizing means comprising an axially-split nozzle having a ribbon-like orifice and said nozzle being positioned at the discharge end of a single acting pump and being constantly open and the axis of said nozzle being tangent to the periphery of rotation of said heating elements.

9. In apparatus for generating oil gas, an oil gas generating chamber, a plurality of electrically heated heating elements provided with a continuous supply of electric current and being rotatably mounted in said chamber, means for causing a regulated quantity of an atomized oil spray to be intermittently projected into said chamber, means for delivering a regulated quantity of water into a grid in said chamber to be flashed into steam, means for causing said oil spray and jets of steam to commingle and form a mixed spray, means for causing said elements to revolve and means for synchronizing the joint contact of said moving heating elements and said mixed spray.

10. In apparatus for generating oil gas, an oil gas generating chamber, a plurality of electrically heated heating elements provided with a continuous supply of electric current and being rotatably mounted in said chamber, means for causing a regulated quantity of an atomized oil spray to be intermittently projected into said chamber, means for intermittently delivering a regulated quantity of water into a grid in said chamber to be flashed into steam, means for causing said intermittent oil and water to be delivered simultaneously into said chamber, means for causing said oil spray and jets of steam to commingle and form a mixed spray, means for causing said elements to revolve in said chamber, and timed mechanism for synchronizing the joint contact of said moving elements and said mixed spray.

11. In apparatus for generating oil gas, an oil gas generating chamber, a plurality of electrically heated heating elements provided with a continuous supply of electric current and being rotatably mounted in said chamber, means for causing a regulated quantity of an atomized oil spray to be intermittently projected into said chamber, means for

intermittently delivering a regulated quantity of water into a grid in said chamber to be flashed into steam, means for causing said intermittent oil and water to be delivered simultaneously into said chamber, means for causing said oil spray and jets of steam to commingle and form a mixed spray, mechanism for causing said elements to rotate and revolve simultaneously, and timed mechanism for synchronizing the joint contact of said moving elements and said mixed spray.

12. In an oil gas generating apparatus, an oil gas generating chamber, a plurality of electrically heated heating elements provided with a continuous supply of electric current and being rotatably and revolvably mounted in said chamber, means for causing a regulated quantity of an atomized oil spray to be intermittently projected into said chamber, means for delivering a regulated quantity of water into a grid in said chamber to be flashed into steam, means for causing said oil spray and jets of steam to be delivered simultaneously into said chamber and to commingle and form a mixed spray, means for causing at least one of said elements to rotate and revolve in said chamber, and means for synchronizing the joint contact of said moving heating element and said mixed spray.

13. In an oil gas generating apparatus, an air-tight oil gas generating chamber, an electrically heated heating element provided with a continuous supply of electric current, rotatably mounted in said chamber, means for intermittently projecting a mixed spray of atomized oil and steam into direct contact with the external surface of said heating element when in an incandescent state, and means for rotating said heating element.

14. In an oil gas generating apparatus, an air tight oil gas generating chamber, an electrically heated heating element provided with a continuous supply of electric current, and being movably mounted in said chamber, means for intermittently projecting a mixed spray of atomized oil and steam into direct contact with the surface of said heating element when in an incandescent state, and means for keeping said element in motion.

Signed at New York in the county of New York and State of New York.

LEONARD B. HARRIS.
